UNITED STATES PATENT OFFICE.

ERNEST F. PFLUEGER, OF AKRON, OHIO.

DESIGN FOR A ROLL-SPRING FOR COLLAR-PAD FASTENERS.

SPECIFICATION forming part of Design No. 20,456, dated January 6, 1891.

Application filed November 29, 1890. Serial No. 373,071. Term of patent 7 years.

To all whom it may concern:

Be it known that I, ERNEST F. PFLUEGER, a citizen of the United States, and a resident of Akron, in the county of Summit and State of Ohio, have invented certain new and useful Improvements in a Design for a Roll-Spring for Collar-Pad Fastenings; and I do declare the following to be a full, clear, and exact description of the invention, such as will enable others skilled in the art to which it appertains to make and use the same, reference being had to the accompanying drawing, and to letters of reference marked thereon, which forms a part of this specification.

The drawing is a representation of the invention and is a perspective view.

This invention relates to the design of the roll-spring of a collar-pad fastener, and it refers to the novel form and configuration thereof, as herein shown and described.

The drawing shows the spring, which is of ribbon form and curved in circular or nearly circular shape, as illustrated. One end of the spring is rounded and the other end *a* squared and has the lateral notches *b b* opposite each other and near the end *a*, the lugs *c c* of the end *a* projecting laterally, as shown.

What I claim is—

The design for a roll-spring of a collar-pad fastener, consisting of the circularly-curved spring having the squared end *a*, the lateral notches *b b*, opposite each other, and the end lugs *c c*, projecting laterally, as shown and described.

In testimony whereof I affix my signature in presence of two witnesses.

ERNEST F. PFLUEGER.
